UNITED STATES PATENT OFFICE

FREDERICK B. BARTELS, OF SAN LEANDRO, CALIFORNIA

CAN EXHAUSTER

Application filed January 15, 1932. Serial No. 586,939.

This invention is a can exhauster and has special reference to a device which is adapted to exhaust occluded air and gases from the liquids or syrups after various fruits, vegetables, or other foods are placed in cans preparatory to sealing or capping.

The main object of the invention is to provide an efficient and simply constructed machine for exhausting occluded gases from the liquids or syrups of fruits and vegetables after being placed in the cans and before sealing or capping.

Another object of the invention is to use metal belts for conveying the canned foods through the exhauster.

A further object of the invention is to provide a can exhauster which will have unusual capacity as related to the size of the machine.

A still further object of the invention is to provide positive means for aligning the metal belts and anti-friction bearings for its support.

Other objects and advantages of the invention will become apparent as the following description is read on the drawings forming a part of this specification and in which similar reference characters are used to designate similar parts throughout the several views and in which:

Fig. 1 is a top plan view of the invention.

Fig. 2 is an enlarged fragmentary view of one end of Fig. 1, showing the method of transferring the cans from one belt to the other and the route traversed by the cans.

Fig. 3 is a longitudinal sectional elevation of one half of the machine.

Fig. 4 is a sectional view through one of the belt teeth taken on line 4-4 of Fig. 5.

Fig. 5 is a section taken on line 5-5 of Fig. 4.

Fig. 6 is a detail view of one sprocket groove.

Fig. 7 is a side elevation of the invention.

Fig. 8 is a plan view showing the adjustable can guides which are adapted to accommodate the machine to various sizes of cans.

Fig. 9 is a view of the can raising cam.

Fig. 10 is a modification of Fig. 9 showing a roller replacing the cam of Fig. 9.

The invention consists primarily of a plu-

rality of anti-parallel metal belts, whereby alternate belts run in the same direction, the belts being transversely aligned and suitably supported throughout their operating length, and positively driven by means of the aligning and supporting element cooperating with grooves formed in the pulleys, transfer means for transferring cans from one belt to the other, intake and discharge means for the cans and steam heating means and steam jets directed against the sides of the cans, the machine being fully enclosed and provided with driving means.

Three belts are shown in the drawings, however it will be understood that any number of belts may be used and they may be of any desired length, therefore the machine may be made of almost unlimited capacity.

As indicated by the arrows on Fig. 1, belts 15 and 16 run toward the left while belt 17 runs toward the right.

The belts are preferably made of corrosion resistant metal such as aluminum bronze, stainless steel or nickel chromium iron alloys although where corrosion is not a factor, ordinary sheet steel, brass or other metals may be used.

The belts are made endless by welding or other known means and are provided with teeth or riders 18 which coincidentally form transverse reinforcements for the belt.

The riders 18 are spaced sufficiently close to prevent appreciable sag in the belt between them when the belt is loaded with cans and consist each of a head member 19 and a body member 20 riveted together and to the belt as indicated at 21. Sockets are formed in the body member 20 to receive the balls 22 which are freely rotatable therein and ride against the head member 19. A ball retaining plate 23 is secured to the body member 20 by means of screws 24, permitting replacement of worn balls, the apertures in plate 23 being just large enough to permit full rotation of the ball. The sides of the riders are arcuately formed and converge toward the lower end as shown at 24, forming teeth which suitably engage in the grooves 25, for positively driving the belt.

Tracks 26 which may be formed of angles as indicated are provided for supporting the belt and to cooperate with the aligning members, for maintaining true alignment of the 5 belts, the tracks being supported on transverse members 27 secured to the standards or legs 28.

Drive pulleys 29 and idler pulleys 30 are provided at both ends of the machine, and 10 are mounted in staggered relation, the drive pulleys being secured on a shaft 31 which is rotatably mounted in bearings 32 and the idler pulleys being secured on a shaft 33 which is rotatably mounted in bearings 34. 15 It will be noted that the drive pulleys for belts 15 and 16 are located at the left hand end of the machine and for belt 17 at the right hand end, viewing Fig. 1.

The return portion 35 of the belt is supported on idle rollers 36 which are rotatably 20 supported on a shaft 37 which is mounted in brackets 38 secured to the standards 28.

The can transfer means consist of thin 25 disks 39 and 40 which are secured at the upper end of spindles 41 which in turn are rotatably mounted between the belts in bearings 42 mounted on legs 28. A bevel gear 43 is secured to the lower end of the spindle for 30 driving the disk which is in contact with the belt at all times, the disk having a sharp peripheral edge 44.

The cans are raised onto the disk by cooperation with a finger 45 or roller 46, which are 35 fixedly secured in a position between the belts.

The heating system consists of steam pipes 47 and 48 which are provided with apertures 49 in the side through which steam is permitted to escape into the cabinet and which is directed against the sides of the cans, the 40 pipes coincidentally forming guards or guides for the cans and having one end flattened and arcuately formed as at 50, and being oppositely disposed, each set being connected by 45 headers 51 which are connected by a suitable supply pipe 52, the portion adjacent the headers also being arcuately formed as at 53, the portions 50 and 53 being adapted to 50 shift the cans into cooperation with the cam fingers 45 or roller 46.

A modification of the can shifting means is shown in Fig. 8 in which the portion 53 is replaced by an adjustable cam 54, the cans 55 cooperating with the edge 55 and being thus urged over onto the roller 46 or finger 45. Slots 56 permit suitable adjustment for different size cans.

The intake and discharge means are disposed on opposite sides of the machine and consist of the intake disc 57 and discharge disc 58 which are similar to the transfer discs 39 and 40, the intake disc requiring no cam finger while the discharge disc has a finger 45 for raising the cans onto the disc.

Turning means for the cans consist of bars 59 formed to semi-circular shape and extending about the periphery of the transfer discs.

The sprockets or pulleys are provided with 60 inwardly converging grooves 60 and the periphery of the pulleys is flattened on both sides of the groove as shown at 61 to prevent kinking of the belt at the riders, and consequent 65 crystallization of the metal at those points.

The drive for the machine consists of a motor 62 which through suitable reduction gearing drives one of the drive pulley shafts 31, which has a bevel gear 63 secured thereon, which cooperates with a bevel gear 65 80 on a shaft 66, which through a pair of bevel gears 67 drives the pulley at the other end of the machine.

The intake and discharge discs are mounted 85 on spindles 68 which have a bevel gear 69 secured thereon which cooperates with a bevel gear 64 on the shaft 31.

The transfer discs are driven by a pair 90 of spiral gears 70 and 71 respectively mounted on the shaft 66 and on a transverse shaft 72, on the other end of which a bevel gear 73 cooperates with the bevel gear 43.

All bearings are outside the heating zone or cabinet, which is formed with sides 74, 95 ends 75, top 76 which is removable and bottom 77 slopes both ways toward the center, where a drain 78 is provided.

The lower cabinet consists of downward extensions 79 of the sides, ends 80, which 100 continue into a guard 81 passing about the pulleys and connecting with the ends 75. An opening through the machine transversely is provided for the transfer disc drives and 105 consists of top ends 82 and bottom 83, which seal off this opening from the cabinet. The bearings 38 are mounted on the standards outside the cabinet as shown, as are also the pulley bearings 34. It will be noted that the only openings in the cabinet to the interior 110 are the intake passage at one end and the discharge passage at the other end.

The direction of travel of the discs and belts are indicated by arrows in Fig. 1. The cans are placed on disc 57 by which they are transferred to belt 15, traveling to the left as viewed in Figs. 1 and 2 and after reaching a point adjacent the transfer disc 40 are deflected by the portion 53 of the steam pipe or the cam 54 onto the finger 45 which raises one side of the can sufficiently to ride on the disc, which carries them about and deposits the cans 86 on the belt 17 which runs in the opposite direction to belt 15, again transferring them by means of disc 39 to belt 16 from 120 which they are deflected onto the discharge disc 58 by the guard 87.

Having described an operable method of constructing and using the invention it will be noted that variations in construction and 125

arrangement of parts which are consistent with the appended claims may be resorted to without detracting from the spirit or scope of the invention or sacrificing any of the advantages thereof.

I claim:

1. A conveyor system comprising a plurality of anti-parallel continuous plane surface belts, each belt being provided on the under surface with equally spaced transverse reinforcing elements provided with a rolling element adjacent each end, said reinforcing elements coincidentally forming aligning elements and tooth elements; tracks cooperating with said elements for supporting and aligning the belt, a head sprocket and a tail sprocket for each belt, the tail sprocket for each belt being located beyond the head sprocket for the next adjacent belt.

2. A conveyor system comprising a plurality of anti-parallel belts having a continuous plane top surface, each belt being provided on the under surface with equally spaced transverse reinforcing elements provided with a rolling element adjacent each end, said reinforcing elements coincidentally forming aligning elements and tooth elements, tracks cooperating with said rolling elements and with the ends of said reinforcing elements for supporting and aligning the belts, a head sprocket and a tail sprocket for each belt provided with grooves for cooperation with said elements, said head sprockets and said tail sprockets being mounted on individually rotatable shafts, spaced apart longitudinally relative to the belts.

3. A conveyor belt comprising an endless metal ribbon having a continuous plane surface and provided with equally spaced, transversely disposed, reinforcing bars on the under surface, and a rolling element mounted adjacent each end of each bar, said bars forming teeth for cooperation with grooves formed in a pulley.

4. A conveyor comprising a head pulley and a tail pulley, each having tooth receiving grooves formed transversely of the periphery, a conveyor belt formed for a continuous metal ribbon having a plane uninterrupted outer carrying surface, and provided with equally spaced teeth on the inner surface coincidentally forming transverse reinforcing members, a supporting and aligning rail for each side of the belt and cooperating with the teeth, the belt being retained in alignment by cooperation of the ends of the teeth with the rails, said teeth having rotatably mounted adjacent each end, a ball for rolling cooperation with the rail.

5. A conveyor comprising a head pulley and a tail pulley, each having tooth receiving grooves formed transversely of the periphery, a conveyor belt formed of a continuous metal ribbon having a plane uninterrupted outer carrying surface, and provided with equally

spaced teeth on the inner surface coincidentally forming transverse reinforcing members, a supporting and aligning rail for each side of the belt cooperating with the teeth, the belt being retained in alignment by cooperation of the ends of the teeth with the rails, said teeth having rotatably mounted adjacent each end, a ball for rolling cooperation with the rail, the rails being oppositely disposed and having a horizontal supporting leg and a vertical aligning leg, the sides of the belt projecting beyond the ends of the teeth and forming a guard over the vertical leg.

6. A conveyor comprising a head pulley and a tail pulley, each having tooth receiving grooves formed transversely of the periphery, a conveyor belt formed of a continuous metal ribbon having a plane uninterrupted outer carrying surface, and provided with equally spaced teeth on the inner surface coincidentally forming transverse reinforcing members, a supporting and aligning rail for each side of the belt and cooperating with the teeth, the belt being retained in alignment by cooperation of the ends of the teeth with the rails, said pulleys having a flattened portion on each side of each groove to obviate undue flexure of the belt at the teeth, while the belt passes about the pulleys.

7. A conveyor comprising a head pulley and a tail pulley, each having tooth receiving grooves formed transversely of the periphery, a conveyor belt formed of a continuous metal ribbon having a plane uninterrupted outer carrying surface, and provided with equally spaced teeth on the inner surface coincidentally forming transverse reinforcing members, a supporting and aligning rail for each side of the belt and cooperating with the teeth, the belt being retained in alignment by cooperation of the ends of the teeth with the rails, the rails being oppositely disposed and having a horizontal supporting leg and a vertical aligning leg, the sides of the belt projecting beyond the ends of the teeth and forming a guard over the vertical leg, said pulleys having a flattened portion on each side of each groove to obviate undue flexure of the belt at the teeth while the belt passes about the pulleys.

8. A conveyor comprising a head pulley and a tail pulley, each having tooth receiving grooves formed transversely of the periphery, a conveyor belt formed of a continuous metal ribbon having a plane uninterrupted outer carrying surface, and provided with equally spaced teeth on the inner surface coincidentally forming transverse reinforcing members, a supporting and aligning rail for each side of the belt and cooperating with the teeth, the belt being retained in alignment by cooperation of the ends of the teeth with the rails, said teeth having rotatably mounted adjacent each end, a ball for

rolling cooperation with the rail, said pulleys having a flatted portion on each side of each groove to obviate undue flexure of the belt at the teeth while the belt passes about the pulleys.

9. A conveyor comprising a head pulley and a tail pulley, each having tooth receiving grooves formed transversely of the periphery, a conveyor belt formed of a continuous metal ribbon having a plane uninterrupted outer carrying surface, and provided with equally spaced teeth on the inner surface coincidentally forming transverse reinforcing members, a supporting and aligning rail for each side of the belt cooperating with the teeth, the belt being retained in alignment by cooperation of the ends of the teeth with the rails, said teeth having rotatably mounted adjacent each end, a ball for rolling cooperation with the rail, the rails being oppositely disposed and having a horizontal supporting leg and a vertical aligning leg, the sides of the belt projecting beyond the ends of the teeth and forming a guard over the vertical leg, said pulleys having a flatted portion on each side of each groove to obviate undue flexure of the belt at the teeth while the belt passes about the pulleys.

10. A conveyor comprising a head pulley and a tail pulley, each having tooth receiving grooves formed transversely of the periphery, a conveyor belt formed of a continuous metal ribbon having a plane uninterrupted outer carrying surface, and provided with equally spaced teeth on the inner surface coincidentally forming transverse reinforcing members, a supporting and aligning rail for each side of the belt and cooperating with the teeth, the belt being retained in alignment by cooperation of the ends of the teeth with the rails, said teeth comprising a body member and a head member fixedly secured together and to the inner surface of the belt, said body member having a socket formed therein adjacent each end and a ball freely rotatable in each socket, and a ball retaining plate removably secured to the body member and having apertures through which the balls project for cooperation with the rail.

50 11. A conveyor comprising a head pulley and a tail pulley, each having tooth receiving grooves formed transversely of the periphery, a conveyor belt formed of a continuous metal ribbon having a plane uninterrupted outer carrying surface, and provided with equally spaced teeth on the inner surface coincidentally forming transverse reinforcing members, a supporting and aligning rail for each side of the belt and cooperating with the teeth, the belt being retained in alignment by cooperation of the ends of the teeth with the rails, the rails being oppositely disposed and having a horizontal supporting leg and a vertical aligning leg, the sides of the belt projecting beyond the ends of the

teeth and forming a guard over the vertical leg, said teeth comprising a body member and a head member fixedly secured together and to the inner surface of the belt, said body member having a socket formed therein adjacent each end and a ball freely rotatable in each socket, and a ball retaining plate removably secured to the body member and having apertures through which the balls project for cooperation with the rail.

12. A conveyor comprising a head pulley and a tail pulley, each having tooth receiving grooves formed transversely of the periphery, a conveyor belt formed of a continuous metal ribbon having a plane uninterrupted outer carrying surface, and provided with equally spaced teeth on the inner surface coincidentally forming transverse reinforcing members, a supporting and aligning rail for each side of the belt and cooperating with the teeth, the belt being retained in alignment by cooperation of the ends of the teeth with the rails, said pulleys having a flatted portion on each side of each groove to obviate undue flexure of the belt at the teeth, while the belt passes about the pulleys, said teeth comprising a body member and a head member fixedly secured together and to the inner surface of the belt, said body member having a socket formed therein adjacent each end and a ball freely rotatable in each socket, and a ball retaining plate removably secured to the body member and having apertures through which the balls project for cooperation with the rail.

13. A conveyor comprising a head pulley and a tail pulley, each having tooth receiving grooves formed transversely of the periphery, a conveyor belt formed of a continuous metal ribbon having a plane uninterrupted outer carrying surface, and provided with equally spaced teeth on the inner surface coincidentally forming transverse reinforcing members, a supporting and aligning rail for each side of the belt and cooperating with the teeth, the belt being retained in alignment by cooperation of the ends of the teeth with the rails, the rails being oppositely disposed and having a horizontal supporting leg and a vertical aligning leg, the sides of the belt projecting beyond the ends of the teeth and forming a guard over the vertical leg, said pulleys having a flatted portion on each side of each groove to obviate undue flexure of the belt at the teeth while the belt passes about the pulleys, said teeth comprising a body member and a head member fixedly secured together and to the inner surface of the belt, said body member having a socket formed therein adjacent each end, and a ball freely rotatable in each socket, and a ball retaining plate removably secured to the body member and having apertures through which the balls project for cooperation with the rail.

14. A conveyor comprising a continuous ribbon of sheet metal having an uninterrupted carrying surface and adapted to withstand the heat and moisture of a can exhausting machine and present a continuous and plane surface whereby tilting or rocking of cans is obviated when carried thereby, said ribbon having teeth coincidentally forming transverse reinforcing elements, at spaced intervals and having sufficient rigidity between the teeth to maintain a substantially plane surface when loaded with cans and the belt is under normal tension while operating over a head pulley and a tail pulley, and supporting rails cooperating with said teeth, said pulleys having a flatted portion on each side of each groove to obviate undue flexure of the belt at the teeth while the belt passes about the pulleys.

15. A conveyor comprising a continuous ribbon of sheet metal having an uninterrupted carrying surface and adapted to withstand the heat and moisture of a can exhausting machine and present a continuous and plane surface whereby tilting or rocking of cans is obviated when carried thereby, said ribbon having teeth coincidentally forming transverse reinforcing elements, at spaced intervals and having sufficient rigidity between the teeth to maintain a substantially plane surface when loaded with cans and the belt is under normal tension while operating over a head pulley and a tail pulley, and supporting rails cooperating with said teeth, the rails being oppositely disposed and having a horizontal supporting leg and a vertical aligning leg, the sides of the belt projecting beyond the ends of the teeth and forming a guard over the vertical leg, said pulleys having a flatted portion on each side of each groove to obviate undue flexure of the belt at the teeth while the belt passes about the pulleys, said teeth comprising a body member and a head member fixedly secured together and to the inner surface of the belt, said body member having a socket formed therein adjacent each end and a ball freely rotatable in each socket, and a ball retaining plate removably secured to the body member and having apertures through which the balls project for cooperation with the rail.

16. A conveyor comprising a continuous ribbon of sheet metal having an uninterrupted carrying surface and adapted to withstand the heat and moisture of a can exhausting machine and present a continuous and plane surface whereby tilting or rocking of cans is obviated when carried thereby, said ribbon having teeth coincidentally forming transverse reinforcing elements, at spaced intervals and having sufficient rigidity between the teeth to maintain a substantially plane surface when loaded with cans and the belt is under normal tension while operating over a head pulley and a tail pulley, and supporting rails cooperating with said teeth, the rails being oppositely disposed and having a horizontal supporting leg and a vertical aligning leg, the sides of the belt projecting beyond the ends of the teeth and forming a guard over the vertical leg, said pulleys having a flatted portion on each side of each groove to obviate undue flexure of the belt at the teeth while the belt passes about the pulleys.

17. A conveyor comprising a continuous ribbon of sheet metal having an uninterrupted carrying surface and adapted to withstand the heat and moisture of a can exhausting machine and present a continuous and plane surface whereby tilting or rocking of cans is obviated when carried thereby, said ribbon having teeth coincidentally forming transverse reinforcing elements, at spaced intervals and having sufficient rigidity between the teeth to maintain a substantially plane surface when loaded with cans and the belt is under normal tension while operating over a head pulley and a tail pulley, and supporting rails cooperating with said teeth, the rails being oppositely disposed and having a horizontal supporting leg and a vertical aligning leg, the sides of the belt projecting beyond the ends of the teeth and forming a guard over the vertical leg, said pulleys having a flatted portion on each side of each groove to obviate undue flexure of the belt at the teeth while the belt passes about the pulleys, said teeth comprising a body member and a head member fixedly secured together and to the inner surface of the belt, said body member having a socket formed therein adjacent each end and a ball freely rotatable in each socket, and a ball retaining plate removably secured to the body member and having apertures through which the balls project for cooperation with the rail.

In testimony whereof I affix my signature.
